United States Patent Office

Des. 219,327
Patented Nov. 24, 1970

219,327

TIRE

Arthur S. Ravenhall, Solihull, England, assignor to The Dunlop Company Limited, Birmingham, England, a corporation of Great Britain

Filed July 25, 1969, Ser. No. 18,415

Claims priority, application Great Britain Feb. 8, 1969

Term of patent 14 years

Int. Cl. D12—14

U.S. Cl. D90—20

FIG. 1

FIG. 2

FIG. 3

FIG. 1 is a perspective view of the tire of my new design;

FIG. 2 is a fragmentary perspective view;

FIG. 3 is a fragmentary plan view.

It is to be understood that the tread and side wall portion shown in full lines in FIG. 1 continue throughout the circumference of the tire.

I claim:

The ornamental design for a tire, as shown and described.
